UNITED STATES PATENT OFFICE.

WALTER SCOTT DOE, OF KENT, OHIO, ASSIGNOR OF ONE-HALF TO AARON L. DAVIS, OF KENT, OHIO.

PENCIL-SHARPENER.

1,233,851.

Specification of Letters Patent.

Patented July 17, 1917.

Application filed September 21, 1916. Serial No. 121,390.

To all whom it may concern:

Be it known that I, WALTER SCOTT DOE, a citizen of the United States, and a resident of Kent, in the county of Portage and State 5 of Ohio, have invented a new and Improved Pencil-Sharpener, of which the following is a full, clear, and exact description.

The object of the invention is to provide a new and improved pencil sharpener, which 10 is simple and durable in construction, cheap to manufacture and arranged to permit quick and convenient sharpening of pencils of various shapes and cross section with a view to produce pointed portions of any de- 15 sired length.

In order to produce the desired result, use 20 is made of a plate provided at the sides with guideways, a cutting blade attached to the said plate and extending across the plate with the cutting edge inward and spaced 25 from the forward edge of the plate, the cutting edge being located in a horizontal plane extending above the top face of the plate, and an abutment member slidably lengthwise in the said guideways on top of the plate, 30 the forward end of the abutment member being spaced from the cutting edge of the cutting blade.

A practical embodiment of the invention 35 is represented in the accompanying drawings forming a part of this specification, in which similar characters of reference indicate corresponding parts in all the views.

Figure 1 is an enlarged plan view of the 40 pencil sharpener;

Fig. 2 is a sectional side elevation of the same on the line 2—2 of Fig. 1;

Fig. 3 is a cross section of the same on the line 3—3 of Fig. 1;

Fig. 4 is a plan view of the cutting blade;

Fig. 5 is a side elevation of the abutment member;

Fig. 6 is an inverted plan view of the same; and

Fig. 7 is a perspective view of the sharpener for sharpening the cutting blade.

The body of the pencil sharpener is in the form of a plate 10 provided at its forward end with a cut-out portion 11 and pro- 50 vided at the sides with upwardly and in-

wardly turned flanges 12 forming guideways 13 on top of the plate 10 at the sides thereof. A cutting blade 14 extends across the plate 10 within the cut-out portion 11 and the cutting edge 15 of the cutting blade 14 extends 55 inward and is spaced from the back wall 16 of the cut-out portion 11. By reference to Fig. 2 it will be noticed that the cutting edge 15 is in a horizontal plane a short distance above the top face of the plate 10. The cutting blade 14 is provided with integral side arms 17 extending in the guideways 13 and the rear ends of the side arms 17 are provided with apertures 18 in register with corresponding apertures 19 formed in the plate 60 10 and its flanges 12. The registering apertures 18 and 19 are engaged by eyes 20 formed on the ends of a U-shaped loop 21 used for suspending the pencil sharpener from a suitable support. The eyes 20 also 65 serve to hold the side arms 17 of the cutting blade 14 locked in position in the guideways 13 thus preventing longitudinal movement of the cutting blade 14 relative to the plate 10. 75

The end of the pencil to be sharpened is abutted against the forward end 24 of an abutment member 25 preferably made in box shape and having its sides provided with flanges 26 slidably engaging the guideways 13 to 80 permit of adjusting the abutment member lengthwise on top of the plate 10 according to the length of the point to be given to the pencil, as will be readily understood by reference to Fig. 2. The bottom of the abutment member 25 is in the form of a spring tongue 27 bearing on the upper face of the plate 10 so as to hold the abutment member 25 in the position in which it is moved by the user of the pencil sharpener. In order to permit 85 convenient sliding of the abutment member 25 toward or from the cutting edge 15 of the cutting blade 14, the top of the abutment member 25 is preferably provided with a roughened portion 28 which affords a firm 90 finger hold to allow the user to move the abutment member forward or backward on top of the plate 10. 95

In order to enable the user of the pencil sharpener to conveniently sharpen the cut- 100

- ting edge 15 whenever it becomes dull use is made of a sharpener 30 removably held in the box-shaped abutment member 25. The sharpener 30 consists of a back plate 31, preferably made of zinc or other metal, and on the top of this back plate 31 is placed a piece 32 of wood or other material having a top surface of an abrading material such as graphite, sand, corundum or the like.
- 10 The abrading piece 32 is held in place on the back plate 31 by having the ends 33 of the latter crimped over onto the top of the piece 32, as plainly indicated in Figs. 2 and 7. The sharpening member 30 is somewhat longer than the abutment member 25 so that the sharpener extends a distance beyond the rear end of the abutment member 25 to permit the user to conveniently remove the sharpener from the abutment member 25 whenever it is desired to sharpen the cutting edge 15 and to permit the user to conveniently replace the sharpener in the abutment member 25 when the sharpener is not in use.
- 15 25 In order to use the pencil sharpener, the end of the pencil to be sharpened is placed on top of the cutting blade 14 with the terminal of the pencil in contact with the forward end 24 of the abutment member 25.
- 30 35 The operator now draws the pencil forward in the direction of the arrow indicated in Fig. 2 and at the same time bears down on the pointed portion so that the cutting edge 15 cuts a slice off the wood of the pencil as well as the lead thereof. This operation is repeated as many times as necessary in order to obtain the desired pointed end on the pencil.
- By adjusting the abutment member 25 nearer to or farther from the cutting edge 15 the length of the pointed portion can be correspondingly reduced or increased to suit the user of the pencil sharpener. It is understood that the shavings produced on drawing the pencil over the cutting edge 15 readily pass through the cut-out portion 11 so that the pencil sharpener is not liable to be clogged up and rendered inoperative by accumulating shavings.
- 40 45 50 55 60 It is further understood that by raising the cutting edge 15 above the top surface of the plate 10 and adjusting the abutment member 25 lengthwise on the plate 10, the desired angularity for holding the pencil is obtained for any desired length of point to be made, as will be readily understood by reference to Fig. 2.
- Having thus described my invention, I claim as new and desire to secure by Letters Patent:—
1. A pencil sharpener, comprising a plate provided at the sides with guideways, a cutting blade extending across the plate and having its cutting edge extending in-

ward and spaced from the forward edge of the plate, the said cutting blade having integral side arms extending in the said guideways, the said plate, guideways and side arms having registering apertures, and a loop having its ends formed into eyes engaging the said registering apertures to fasten the side arms in position on the plate and its guideways.

2. A pencil sharpener, comprising a plate provided at the sides with guideways, a cutting blade extending across the plate and having its cutting edge extending inward and spaced from the forward edge of the plate, the said cutting blade having integral side arms fastened in the said guideways, and an abutment member on top of the plate and mounted to slide lengthwise in the said guideways nearer to or farther from the cutting edge of the said cutting blade.

3. A pencil sharpener, comprising a plate provided at the sides with guideways, a cutting blade extending across the plate and having its cutting edge extending inward and spaced from the forward edge of the plate, the said cutting blade having integral side arms fastened in the said guideways, and an abutment member on top of the plate and mounted to slide lengthwise in the said guideways nearer to or farther from the cutting edge of the said cutting blade, the said abutment member having a spring tongue at the bottom and bearing on the said plate.

4. A pencil sharpener, comprising a plate provided at the sides with guideways, a cutting blade extending across the plate and having its cutting edge extending inward and spaced from the forward edge of the plate, the said cutting blade having integral side arms fastened in the said guideways, and an abutment member on top of the plate and mounted to slide lengthwise in the said guideways nearer to or farther from the cutting edge of the said cutting blade, the said abutment member being hollow and closed at the forward end and open at the rear end for the reception of a sharpening device for the cutting blade.

5. A pencil sharpener provided with a support having guideways and carrying a cutting knife and an abutment member made of a piece of sheet metal shaped to form a box closed at one end and open at the other end, the bottom of the box forming a spring tongue and the sides having outwardly extending flanges engaging the guideways of the support.

6. A pencil sharpener, comprising a plate provided at its forward end with a cut-out portion, the sides of the plate having turned over flanges forming guideways, a cutting blade attached to the said plate and extend-

ing across the said cut-out portion, the cutting edge of the said blade being spaced from the back wall of the said cut-out portion, the cutting edge extending in a horizontal plane above the top face of the plate, and an abutment member slidably lengthwise in the said guideways on top of the

plate, the forward end of the abutment member being spaced from the cutting edge of the cutting blade.
